CLAIM

The ornamental design for a laparoscopic tool for inserting a mesh prosthesis, as shown and described.

DESCRIPTION

FIG. 1 is an exterior perspective view of a laparoscopic tool for inserting a mesh prosthesis showing my new design;

FIG. 2 is a top plan view thereof;

FIG. 3 is a left side elevational view thereof;

FIG. 4 is a front elevational view thereof; and,

FIG. 5 is a rear elevational view thereof.
